TOILET KIT

Katherine Louise Lee and Duryea Bensel,
Los Angeles, Calif.

Application December 22, 1945, Serial No. 636,742

1 Claim. (Cl. 240—6.45)

1

This invention relates to cosmetology and more particularly to toilet kits of the type known as "compacts" which provide for a supply of "make up" material such as powder, and a suitable applicator and mirror.

An object of this invention is to provide a toilet kit embodying means by which ample illumination of the user's face can be effected in front of the mirror for same to be used in carrying out the "make up" operation under conditions in which the necessary light for the purpose is not present from extraneous sources, thus enabling the user to apply powder or other cosmetic material in any dark location, whereby to greatly add to the convenience of using the toilet kit, and permitting its use at any time regardless of the lack of other light for the purpose.

Another object of this invention is to provide a toilet kit of the above described character in which the illumination is obtained by the automatic lighting of an electric lamp suitably located with respect to the mirror-supporting closure of the kit, and in response to opening of the closure to a position convenient for viewing the reflection of the user's face in the mirror, the lamp being preferably extinguished automatically when the closure is moved to a second open position also convenient for use of the mirror, thus avoiding needless waste of the electrical energy from self-contained batteries in the kit, when there is ample illumination from an extraneous source for the "make up" operation.

A further object of this invention is to provide a toilet kit whose functional advantages as above set forth are attained with a small, flat structure of neat and attractive appearance capable of being safely and conveniently carried in a handbag or about the person in the usual manner of such accessories.

With these and other objects in view, the invention resides in the combinations, arrangements and functional relationships of elements set forth in the following specification and particularly pointed out in the appended claim.

In the accompanying drawing,

Figure 1 is a plan view of one form of toilet kit embodying this invention, and illustrating the kit in its illuminating, open position;

Figure 2 is a vertical sectional view taken on the line 2—2 of Figure 1;

Figure 3 is a sectional view similar to Figure 2 and showing the toilet kit in closed position;

Figures 4 and 5 are fragmentary detail sectional views taken on the lines 4—4 and 5—5, respectively, of Figure 1;

2

Figure 6 is a diagrammatic view of the electric circuit embodied in the invention;

Figure 7 is a sectional view similar to Figure 3, and illustrating a modified form of dry battery and mounting thereof, embodied in the invention; and

Figure 8 is a fragmentary sectional view taken on the line 8—8 of Figure 7.

Referring specifically to the drawing, and particularly to Figures 1 to 6, inclusive, this form of the invention comprises a receptacle which may be constructed of plastic or other suitable material to provide a flat, rectangular body section 10 and a cover section 11. The body section 10 is formed to provide a flat bottom wall 12, side walls 13, and a front wall 14, the top and rear of the body section being open. The body section is provided with a longitudinal partition 15 spaced from the rear thereof, and with transverse partitions 16, all so as to divide the body section into a central compartment 17 for the cosmetic material such as face powder, and side compartments 18 for suitable dry batteries 19. A removable lid 20 has a friction fit between the side walls 13 and front wall 14 and spans the compartments 17 and 18 in order to conceal the batteries 19 and provide access to the powder compartment 17 through a finely screened opening 21 which is sufficiently depressed into the powder compartment to provide a recess 22 for a powder puff or pad (not shown).

The cover section 11 is flat and of rectangular outline, and projects tangentially along one longitudinal edge from a cylindrical hub 23 co-extensive in length with the cover section and snugly received between the side walls 13 of the body section 10 in the space between the longitudinal partition 15 and the open rear of the body section, so as to close same and form a smooth curved continuation of the body section as shown in Figures 2, 3 and 5.

The hub 23 is provided with an axial bore 24 therethrough, into the ends of which project pivot pins 25 from the side walls 13 of the body section, 45 to hingedly mount the cover section on the body section to occupy the closed position shown in Figure 3, and various open positions, of which one is shown in Figures 1, 2 and 5. Cemented or otherwise secured to the inside of the cover section 11 is a mirror or reflector 26 of glass, metal, or other suitable material, the lower central portion 27 of which is either frosted, coated or otherwise treated to render it non-reflecting directly in the rear of a miniature type of electric lamp 28 50 whose base 29 is mounted in a socket 30 fixed in

a diametric bore 31 in the hub 23, and having its center contact 32 engaged by the center contact 33 of the lamp 28 when screwed into the socket as shown in Figures 2 and 3.

Projecting from the front wall 14 of the body section 10 into the battery compartments 18 are spring contact members 34 and 35 permanently connected electrically by a bridging strip 36 embedded in such wall. Projecting from the partition 15 into the battery compartments 18 are spring contact members 37 and 38 electrically connected by suitable fasteners 39 to fixed spring contact members 40 and 41 projecting from the other side of the partition 15 into yielding engagement with the electrically insulating periphery of the hub 23 in which are embedded segmental contacts 42 and 43 adapted for simultaneous wiping engagement with the respective contact members 40 and 41 during movement of the cover section. Conductors 44 and 45 connect the contacts 43 and 42 with the socket 30 and socket contact 32 respectively, to supply current to the lamp 28 in the operation of the invention which is as follows:

With the batteries 19 supported by the respective pairs of contact members 34, 37 and 35, 38 in series therewith, and with the cover section 11 closed as shown in Figure 3, the lamp 28 is received in a laterally offset portion of the partition 15, and the movable contacts 42 and 43 are out of engagement with the contacts 40 and 41 so as to disrupt the electrical circuit of the lamp 28 so that same is extinguished.

Upon opening the cover section 11 to the approximate position shown in Figures 2 and 5, in which the mirror 26 is disposed at a convenient angle for the user to view the face in the mirror, the contacts 42 and 43 have been rotated into engagement with the contacts 40 and 41 so as to complete the electrical circuit to the lamp 28 as follows:

From one battery 19 through contact member 37, fastener 39, contact member 40, movable contact 42, conductor 45, socket contact 32, lamp 28, socket 30, conductor 44, movable contact 43, contact member 41, fastener 39, contact member 38, other battery 19, contact member 35, contact strip 36, and contact member 34 to the first battery, all of which is clearly shown in Figure 6.

The illumination now provided by the lamp 28 is ample for the user to clearly view the face in the mirror 26 in an otherwise totally dark location, so as to permit application of powder and/or other cosmetic to the face as desired. For daytime use or use under such conditions as provide the necessary illumination independently of the lamp 28, the latter will be automatically extinguished by disengagement of the contacts 42 and 43 from the contacts 40 and 41 in response to a slight further opening movement of the cover section 11 from the position shown in Figure 2, thus preventing unnecessary waste of energy from the batteries 19 so as to prolong the life thereof. In this last mentioned position, the mirror 26 will still be disposed at a convenient angle for the user to view the face in the mirror and apply the cosmetic as desired.

In Figures 7 and 8 there is illustrated a cross sectionally non-circular form of battery 19a which is relatively flat to reduce the thickness of the receptacle. The outside or shell terminal of this battery is in the form of a tab 45a having an opening in which is wedged a prong 46 of a spring contact member 47 mounted in the front wall 14a of the body section 10a. The center or carbon 48 of the battery has its projecting end 15a portion provided with a transverse opening in which is wedged the prong 49 of a spring contact member 50 embedded in the partition wall 15a of the body section for co-action with the contact member 47 in firmly supporting the battery from the contact members with the latter placed under sufficient stress by forcing the battery terminals onto the prongs 46 and 49, for the battery to be securely held under tension against displacement from the contact members. In other respects this form of the invention is similar in construction to that previously described, so that further detailed description will be dispensed with.

We claim:

A device of the class described comprising: a rectangular body section of electrical insulating material having a bottom, front and side walls rising from the bottom, and open at the back, with the body partitioned to provide a central cosmetic compartment and side battery compartments; a cover section of electrical insulating material having a cylindrical hub with a bore therethrough and snugly fitting between said side walls to close the back of the body section; pins supported in said side walls and entering the ends of said hub to hingedly mount the cover section on the body section; a reflector on the inner side of the cover section; said hub having means to support a lamp therein; contacts in the hub adapted to be engaged by the lamp; conductors connected to said contacts and extending through said bore; peripheral contacts supported on the hub opposite one end of said battery compartments, and being connected, respectively, to said conductors; a bridging conductor extending along said front wall and having battery contacts exposed in the other end of said battery compartments; and other battery contacts in said one end of the battery compartments, adapted to be engaged by said peripheral contacts in a predetermined open position of said cover section, to supply current from the batteries in said battery compartments to a lamp supported in the hub.
